UNITED STATES PATENT OFFICE.

THOMAS A. NATHANS, OF NEW YORK, N. Y.

ELECTRIC RELAY OR REPEATER.

1,151,707.

Specification of Letters Patent. Patented Aug. 31, 1915.

Application filed July 25, 1907. Serial No. 385,443.

To all whom it may concern:

Be it known that I, THOMAS A. NATHANS, a citizen of the United States, residing at New York, in the county of New York and State of New York, have invented certain new and useful Improvements in Electric Relays or Repeaters, of which the following is a full, clear, and exact specification.

My invention relates to improvements in electric relays, or repeaters, and to an improved method of reproducing or amplifying varying electric currents.

Although my invention is particularly well adapted for telephone systems, it may be applied to various other devices and apparatus, such as to phonographs, the tele-harmonium, wireless telegraphy, etc.

One object of my invention is to produce an improved method of operating relays and a construction of relays which will be very sensitive and accurately reproduce, or amplify, as desired, the variations in the primary circuit.

A further object of my invention is to produce a repeater in which parts having mechanical inertia in operation will be eliminated. The presence of mechanically moving parts in telephone repeaters is decidedly objectionable not only on account of the frequent inspection, adjustment and repair which is necessary, but also on account of their inefficiency and failure to reproduce currents without material distortion or avoid what is commonly known as "sing-
ing." My invention overcomes these objections, and other disadvantages of such repeaters or relays, and at the same time I obtain a construction which is simple, durable and which requires only slight occasional inspection.

In carrying out my invention, I subject a material to the influence of current fluctuations in the primary or transmitting circuit, and affect the resistance of such material in accordance with variations of current in the primary circuit. This material consequently affects the current in its circuit by reason of variation of its resistance. The current fluctuations may thereby be reproduced and if desired may be greatly amplified. This action depends upon the material which is subjected to the influence of the primary circuit or current, and I have found that certain of the metallic oxids, such as magnetite for example, are ex-

tremely sensitive in resistance to the influence of varying currents. From various experiments I have made and various practical tests, I believe the change in resistance of the magnetite is due to variation in temperature of the material when subjected to the heat varying influences of the varying currents.

My invention will be understood from the following description and accompanying drawings, in which—

Figure 1 is a diagram illustrating my invention generally with reference to a primary and secondary circuit; Fig. 2 illustrates my invention diagrammatically; and as applied to a single circuit; Figs. 3 to 7 are diagrams showing various forms of connection of the sensitive resistance material and circuits; Fig. 8 is a diagram showing my invention used as a repeater in a two-way telephone circuit; Fig. 9 is a diagram showing my invention applied as a relay in a long distance telephone system; Fig. 10 is a diagram similar to Fig. 9, except that the usual operator's cord circuits are replaced by means embodying my invention; and Fig. 11 is a plan view of a simple form of unit embodying the sensitive resistance material and heating coil.

Referring to Fig. 1, a translating device of any desired form is shown at 1, in circuit with a source of current 2. The circuit includes a coil 4, which surrounds a material 3. This material may be of magnetite or any other substance or composition which is sensitive in change of resistance to the influence of current fluctuations in the coil 4. The material 3 may be in the form of a solid piece or finely divided and incased in a tube, or may be in any other suitable form. This material is shown in Fig. 1 as connected in series with the secondary circuit 5 containing a source of current 6 and the receiving apparatus 7 of any desirable form. In order to adjust the strength of current or change in current values in the secondary circuit, an adjustable resistance 8 may be connected therein. Also, if desired, the source 6 may be adjustable as well as source 2, or the number of turns in coil 4.

The method of operation of the form shown in Fig. 1, is as follows: The fluctuations due to the source of sending apparatus 1 will cause the current in the primary circuit to fluctuate. These fluctuations are

reproduced in the secondary circuit by reason of the effect of the current through the windings 4 upon the material 3, the resistance of this material changing in accordance with the fluctuations of the primary circuit and thereby effect a change of current in the secondary circuit. The currents are accurately reproduced without material distortion, and the fluctuations may be increased or decreased according to adjustment and relation of the parts. With the parts so related and adjusted as to amplify the fluctuations, the invention becomes of great advantage when used as a relay or repeater in telephone circuits, and in analogous arts. As above stated, I believe this change in resistance of material 3 is due to instantaneous change in the temperature thereof in accordance with the current fluctuations in the primary circuit. The fluctuations in current which are thus reproduced in the secondary circuit will affect the receiving apparatus correspondingly, as is well understood.

In Fig. 2 only one circuit is illustrated, and in this case the sensitive resistance material 3 is shown connected in series with the transmitting device 1, receiving apparatus 7 and source 2. In this arrangement the sensitive resistance material may serve to amplify the current fluctuations, which fluctuations are originally produced by the transmitting device. When the transmitting device is used, current fluctuations are created in the circuit as is well understood. These fluctuating currents, however, in passing through the sensitive resistance material 3 will cause instantaneous variation in temperature of this material which will vary in resistance accordingly. This change of resistance will therefore take place in synchronism, or at least in practical synchronism, with the current fluctuations produced by the transmitting device and may therefore serve to greatly amplify the current fluctuations, and so increase the action of or effect upon the receiving apparatus. Of course the relations of the various parts will control the effect produced, and any suitable form, means or method of adjustment may be resorted to to secure the best relationships to produce the particular object in view. If it be desired to have the resistance of the sensitive material low, and to have comparatively large flow of current, the cross section of the sensitive material may be of course increased, or several such resistances may be connected in parallel as indicated in Fig. 3. The current may of course be decreased by connecting the sensitive resistances in series as shown in Fig. 4.

In Fig. 5, the sensitive resistances are shown connected in parallel, and the heating coils of a primary circuit are shown connected in parallel.

In Fig. 6, the resistances are shown connected in series and the heating coils also connected in series.

In Fig. 7, the resistances are shown connected in parallel and the heating coils in series, and it is evident that various other combinations may be made as desired.

In Fig. 8, my invention is shown applied to a two-way telephone circuit. It is common practice to use repeating coils in the operator's cord circuits, or trunk circuits in common battery, or central energy telephone exchanges, etc. In Fig. 8 such repeating coils are replaced by repeaters embodying my invention. A common battery is shown at 9, and in series therewith at opposite terminals are shown connected the sensitive resistances 3, 3'. From the upper terminal of the battery extends a connection to the coil or winding 4 surrounding the resistance 3 and from this coil a connection extends to the distant station at the right. From the lower terminal of the battery a connection is made to the winding or coil 4' which surrounds the resistance 3', and from this coil a connection extends to a distant station at the left. A terminal of resistance 3 is connected to the station at the left and a terminal of resistance 3' extends to the distant station at the right, as shown. The apparatus at the two stations is shown as comprising the transmitters 10, 10', the receivers 11, 11', the call bells 12, 12', the condensers 13, 13', the instrument induction coils 14, 14', and the receiver hooks 14^a, 14^b. The connections are shown as having been completed and in condition for talking between the two stations. Starting from the transmitter 10, the fluctuations in current created thereby will traverse the following circuit:—from the lower terminal of battery 9 through the coil 4', transmitter 10, through one of the contacts made by hook 14^a, through one element of induction coil 14, thence through the sensitive resistance 3 to the upper terminal of the battery 9, and thence through the battery to the other terminal. The resistance 3 in this circuit may serve to amplify the fluctuations as referred to in connection with Fig. 2. The fluctuations in this circuit will be reproduced in the circuit extending to the right hand station by the variation of the resistance 3', owing to the influence of the fluctuating currents in the coil 4', as explained with reference to Fig. 1. The fluctuating currents in coil 4 of this secondary circuit may increase the effect of variation in resistance 3, and thereby still further increase the magnitude of the fluctuations. The circuit extending to the right hand station in which the fluctuating current will be reproduced is as follows: from battery 9 through the sensitive resistance 3', through one element of induction coil 14', through a contact of hook 14^b, transmitter 13,

10', through coil 4 and then to battery 9. The fluctuating currents through the circuit described are introduced by the induction coil 14' into the local circuit containing the receiver 11'—which local circuit is as follows:—from one element of the induction coil, to receiver 11', through condenser 13', transmitter 10', through receiver hooks, back to the said element of the induction coil. It will therefore be seen that the fluctuations impressed by the transmitter 10 will be transmitted to the receiver at the right hand station, and my invention serves as a repeater, or relay to amplify the fluctuations. It will be seen that when the transmitter 10' is in operation, the fluctuations will be transmitted to receiver 11 in a corresponding manner, and the circuits being similar they need not be particularly described.

In Fig. 9, I have shown my invention applied to a two-way long distance telephone system, the connections being shown completed for conversation between the two stations. In this figure the apparatus at the two stations and their connections are the same as described with reference to Fig. 8; also the form of two-way repeater or relay shown as located in the middle of the figure is the same form as shown in Fig. 8, and this relay will be located at any suitable point between the two distant stations. I have shown the usual circuits of the operator's cords comprising the battery 15 and repeating coil elements 16. I have also shown at 17, 17, the usual repeating coil elements for taking the battery off the line. The long distance lines then extend to the ordinary repeating coil elements 18 for the purpose of introducing my improved relay or repeater. On the other side of the relay are the corresponding repeating coil elements 18', the long distance line, the repeating coil elements 17', and the corresponding battery 15' and repeating coil elements 16' of the operator's circuits. The operation of such a system will be understood by those skilled in the art, and the action of my improved relay or repeater will be understood from the foregoing description.

In Fig. 10, I have shown the system of Fig. 9 excepting the operator's cord circuits which are replaced by repeaters embodying my invention. That is, the battery 15 and repeating coil elements 16, and the battery 15' and repeating coil elements 16' of Fig. 9 are replaced by repeating apparatus and connections of the form shown in Fig. 8. Thus, in Fig. 10, I have not only shown the long distance relay as embodying my invention, but I have shown the operator's cord circuits as also embodying my invention, and the action therein is similar to that already described.

Fig. 11 shows a convenient form of construction of the sensitive resistance 3 or 3'

and the heating coils 4 or 4'. The sensitive resistance is shown as provided with the terminals 19, 19' at the ends thereof, in the form of metallic bands or collars which may be electrolytically deposited on the material, 70 and the terminals of the heating coil are shown at 20, 20' in the form of similar metallic bands or collars. This unit is thus in a form well adapted to be placed in terminal clips of the circuits with which the sensitive 75 resistance and heating coil are to be connected.

Although I have illustrated my invention applied to a particular form or forms of telephone systems, it will be understood that 80 my invention is applicable to various other systems, and the form of connections may be variously arranged. Also, although I have shown my invention applied to telephone systems as an instance of one application, it 85 will be understood that it may be applied to various other devices and apparatus. It will also be understood that the form of the sensitive resistance material and the manner in which the heating coil may be associated 90 therewith, is susceptible of various modifications. Instead of using magnetite as the sensitive material, it will be understood that any other substance may be used which is sufficiently sensitive to produce the results 95 desired.

I have shown my invention applied to devices or apparatus in which the source of energy is electric, but in some forms of embodiment there may be a varying heat source 100 produced independently of electric energy, and to which variation in heat the sensitive resistance material may be subjected. The change in resistance in accordance with the heat variation may then affect the current 105 in a circuit and so reproduce current fluctuations in accordance with the heat fluctuations.

Having thus described my invention, I declare that what I claim as new and desire 110 to secure by Letters Patent, is,

1. In a telephone system, a relay comprising in combination a transmitting circuit having a heating means, a secondary circuit, and a substance containing magnetite in operative relation with said heating means for controlling the conductivity of said substance in response to variations of the current in the transmitting circuit. 115

2. In a telephone system, a relay comprising in combination a circuit having means for changing the transmitted telephonic currents into heat energy, an element constituted of magnetite in operative relation with said means, a derived circuit electrically influenced by said element, and a source of electrical energy, said source and said element being connected in series in said derived circuit. 120

3. In a telephone transmitter the combina- 130

- tion of a sending circuit; a receiver and a conducting element composed of a metallic oxide included in said circuit; means for raising said element to any desired temperature comprising a heating circuit provided with a coil in proximity to said element; a telephone transmitter in said heating circuit; and means to control the current through said coil, substantially as described.
- 5 10 4. In a telephone transmitter the combination of a sending circuit; a receiver and a conducting element composed of a metallic oxide included in said circuit; means for raising said element to any desired tempera-
ture comprising a heating circuit provided 15 with a coil in proximity to said element; a telephone transmitter in said heating circuit; means to actuate the same from a distant station; and means to control the current through said coil, substantially as de- 20 scribed.

In testimony whereof I affix my signature, in presence of two witnesses.

THOMAS A. NATHANS.
